UNITED STATES PATENT OFFICE.

HENRY KLEB, OF ELIZABETH, NEW JERSEY.

MOLDING MACHINE.

Application filed July 6, 1923. Serial No. 649,854.

To all whom it may concern:

Be it known that I, HENRY KLEB, a citizen of the United States, residing at Elizabeth, in the county of Union and State of New Jersey, have invented new and useful Improvements in Molding Machines, of which the following is a specification.

This invention relates to molding machines.

10 One object is to provide a molding machine particularly adapted to produce a multiple number of pots in one operation, and thereby reduce the cost of production.

The invention consists in the combination 15 and arrangement of parts hereinafter more fully described, illustrated in the accompanying drawing; and particularly pointed out in the appended claims, it being understood that changes may be made in the form, 20 proportion, size and minor details without departing from the spirit or sacrificing any of the advantages of the invention.

In the drawings, in which like characters of reference designate corresponding parts 25 in the several views:

Figure 1 is a side elevation, partly broken away, of a molding machine constructed in accordance with this invention.

Figure 2 is a detail view of a plunger, mold 30 and ejector means.

Figure 3 is a view of the tilting mechanism taken substantially on line A—A.

Figure 4 is a view of an agitator arrangement taken substantially on line B—B.

35 Figure 5 is a transverse sectional view of the molding machine, showing relation with the various parts and taken substantially on the line C—C.

Referring now more particularly to the 40 accompanying drawing, the character 20 indicates a frame, which serves as a support for a crank shaft 16. Sleeved on the crank shaft 16 is a series of connecting rods 13. The upper ends of the connecting rods 45 13 are provided with sectional bearing sleeves 14 and the lower ends of the connecting rods are connected by suitable joints 12 to form spindles 3, which are threaded to cause a rotary motion during the up and 50 down movement of the spindles 3, which are guided in vertical bearing boxes 21. The bearing boxes 21, which are mounted in a horizontal guide bar 21^a of the frame 20, are threaded to engage the threads of the 55 spindles to produce the said rotary motion.

Secured to the lower end of the form

spindle 3 are plungers 2, and the said form spindles also carry yieldably mounted compressor plates 6, located immediately above the plungers 2 engaged by springs 7 interposed between the cam presser plates 6 and collars 8 and adapted to urge the compressor plates 6 downwardly. The form spindles pass through the collars which may be connected with the plunger 2 by pins 65 9. The pins 9 serve as retaining means for the spring 7, but the collars 8 may be fixed to spindles as shown with the pins carried by the compressor plates and extending through collar 8.

70 Journaled suitably in the frame is a square shaft or supporting member 15 provided with grooves 11^a for ejector spindle ball 10, and detachably retained in said grooves by means of a collar or cap 11. The prolongation of ejector spindle ball 10 is the ejector spindle 5, which is threaded to cause a rotary motion when moved up and down, attached to ejector valves 4, forming a part of molds 1, which are mounted in the frame 20. 80 Brackets 22 serve as guide and brace for ejector spindle 5 and are interiorly threaded and suitably fastened to the frame. The lower horizontal supporting member 15 is suspended from the end cranks 16^a of the 85 crank shaft 16 by upper and lower links 19 and 19^a. The crank shaft 16 is adapted to raise the ejectors simultaneously when the plungers 2 are withdrawn from the molds by the crank shaft in the operation of molding machine, and the plungers and ejectors 90 will be rotated during their upward and downward movements. The horizontal supporting bar is guided in slot boxes 18 suitably secured to the frame 20 at the ends 95 thereof.

95 Journaled in the frame mid-way between the top and bottom is a shaft 37, driven by a pulley 30 and provided at its ends with flanges 31 forming eccentrics and consisting of disks having eccentrically connected to them pitman 35, which extend to and are pivotally connected with sliding rods or bars 35^a. The sliding rods or members 100 carry a tilting rod 32 and operate in guides 36, consisting of fixed arms or supports. These slideable rods tilt the pot in an inverted position over a fixed bar 38 on to a conveyor belt 23. The crank shaft is driven by means of a pulley 17.

105 Mounted on top of frame 20, alongside of crank shaft 16 and driven by means of

pulley 29 is the feeding arrangement consisting of a hopper 27 and a set of rollers 28 journaled in the hopper and provided with pockets adapted to form plastic material into balls, which are delivered by the rollers to a worm-shaped conveyor 24, enclosed in a casing 25.

At convenient distances in said casing are attached tubular chutes 26, which lead to the mouths of the molds. At the end of each of the tubular chutes is attached a rotary dislodging device 33, operated by means of connecting rods 34 connected at their upper ends with the crank shaft 16 and at the lower ends to crank arms 34^a of a shaft or pivot 33^a of the dislodging device 33. The dislodging device 33 is adapted to carry the crank 34 over the dead center so that the dislodging device will be rotated by the upper crank shaft 16.

What I claim is:—

1. A multiple pot molding machine of the character described, comprising a frame, a set of molds, a crank shaft journaled in the frame above the molds, plungers operatively connected with the crank shaft and movable into and out of the molds, means movable with the plungers for closing the mouth of the molds, ejecting means located at the bottom of the molds and operating in timed sequence with the plungers for removing the completed pots from the molds, a conveyor, and means for tilting the completed pots on to the conveyor after the said pots have been ejected from the molds.

2. A multiple pot molding machine of the character described, comprising a frame, a series of molds, a crank shaft mounted in the frame above the molds, plungers operatively connected with the crank shaft and movable into and out of the molds, ejecting means located at the bottom of the molds and connected with and actuated by the said crank shaft to eject the completed pots from the mold as the plungers are withdrawn, a conveyor, and means for delivering the pots on to the conveyor after the pots have been ejected from the molds.

3. A multiple pot molding machine of the character described, comprising a frame, a set of molds, a crank shaft mounted in the frame above the molds, plungers having spindles guided in the frame and connected with the crank shaft for moving the plungers into and out of the molds, ejectors arranged at the bottoms of the molds and having spindles guided in the frame and extending downwardly from the said molds, a supporting member carrying the ejector spindles, and means for connecting the supporting member with the crank shaft for operating the ejectors to remove the molded pots from the molds, as the plungers are withdrawn.

4. A multiple pot molding machine of

the character described, comprising a frame, a set of molds, a crank shaft mounted in the frame above the molds, plungers having spindles guided in the frame and connected with the crank shaft for moving the plungers into and out of the molds, ejectors arranged at the bottoms of the molds and having spindles guided in the frame and extending downwardly from the said molds, a supporting member carrying the ejector spindles, means for connecting the supporting member with the crank shaft for operating the ejectors to remove the molded pots from the molds as the plungers are withdrawn, a conveyor located at one side of the molds, a tilting rod arranged at the opposite side of the molds, and eccentric means connected with the tilting rod for actuating the same to tilt the pots on to the conveyor.

5. A multiple pot molding machine of the character described, comprising a frame, a set of molds, a crank shaft mounted in the frame above the molds, plungers having spindles guided in the frame and connected with the crank shaft for moving the plungers into and out of the molds, ejectors arranged at the bottoms of the molds and having spindles guided in the frame and extending downwardly from the said molds, a supporting member carrying the ejector spindles, means for connecting the supporting member with the crank shaft for operating the ejectors to remove the molded pots from the molds as the plungers are withdrawn, a conveyor located at one side of the molds, a tilting rod arranged at the opposite side of the molds, eccentric means connected with the tilting rod for actuating the same to tilt the pots on to the conveyor, and fixed means arranged in the path of the tilted pots for causing the same to be inverted on the conveyor.

6. A multiple pot molding machine of the character described, comprising a frame, a set of molds, a hopper, means located in the hopper for forming material into balls, a conveyor receiving the material from the hopper and provided with chutes for delivering balls to the molds, means for controlling the delivery of the balls to the molds, and means for molding the balls into pots.

7. A multiple pot molding machine of the character described, comprising a frame, a set of molds, a hopper having rollers provided with means for forming plastic material into balls, a conveyor receiving the balls from the hopper and provided with chutes extending to the molds, devices operating in the chutes for controlling the delivery of the balls to the molds, and means for molding the material.

8. A multiple pot molding machine of the character described, comprising a frame,

a set of molds, a crank shaft journaled in the frame above the molds, plungers cooperating with the molds, means for connecting the plungers with the crank shaft for raising and lowering the plungers, means co-acting with the said means for causing a rotary movement of the plungers when the same are raised and lowered.

9. A multiple pot molding machine of the character described, comprising a frame, a set of molds, a crank shaft journaled in the frame above the molds, plungers operatively connected with the crank shaft and movable into and out of the molds, ejecting means located at the bottom of the molds and operating in timed sequence with the plungers for removing the completed pots from the molds, and means for rotating the plungers and the ejecting means simultaneously with the upward and downward movement of the same.

10. A multiple pot molding machine of the character described, comprising a frame,

a set of molds, a crank shaft mounted in the frame above the molds, plungers having spindles connected with the crank shaft for moving the plungers into and out of the molds, said spindles being threaded, threaded guiding means receiving the spindles and engaging the threads of the spindles for rotating the plungers when the same are moved upwardly and downwardly, ejectors arranged at the bottoms of the molds and having threaded spindles extending downwardly from the same, a supporting member carrying the ejector spindles, threaded means for engaging the threads of the ejector spindles for causing the rotation of the ejectors when the same are raised and lowered, and means for connecting the supporting member with the crank shaft for raising and lowering the ejectors.

In testimony whereof I have hereunto set my hand.

HENRY KLEB.
